United States Patent [19]

Doi

[11] Des. 267,094

[45]  Nov. 30, 1982

[54] MAGNETIC CARD FOR MICROWAVE OVEN

[56]

References Cited

U.S. PATENT DOCUMENTS

[75] Inventor: Keiichiro Doi, Osaka, Japan

D. 221,282	7/1971	Miller et al.	D14/40
2,272,366	2/1942	Dickenson	235/494
3,359,985	12/1967	Luscher	D14/40 X
4,024,379	5/1977	Pfost et al.	235/380
4,102,492	7/1978	Gold et al.	235/375

[] Term: 14 Years

Primary Examiner—Susan J. Lucas

[21] Appl. No.: 83,959

Attorney, Agent, or Firm—Flehr, Hohbach, Test,
Albritton & Herbert

[22] Filed: Oct. 11, 1979

CLAIM

[30] Foreign Application Priority Data

The ornamental design for a magnetic card for microwave oven, as shown and described.

Apr. 12, 1979 [JP] Japan 54-15215

DESCRIPTION

[51] Int. Cl. ..... D14—02

FIG. 1 is a front elevational view of the magnetic card for microwave oven showing my new design;

[52] U.S. Cl. D14/117

FIG. 2 is a back view thereof;

[58] Field of Search D14/40; 235/375, 419,

FIG. 3 is a right side elevational view thereof, the left

235/487, 493, 494, 495, 379, 380

side being identical; and

FIG. 4 is an end view thereof.

FIG_2

FIG_3

FIG_1

FIG_4